SANDBLASTING NOZZLE

Thomas Sorrentino, New York, N. Y., assignor to
Oceanic Ship Scaling Co., Inc., Brooklyn, N. Y.,
a corporation

Application March 28, 1944, Serial No. 528,436

15 Claims. (Cl. 51—11)

This invention relates to sand blasting nozzle. An object of this invention is to provide a nozzle for sand blasting, and provided with a water jacket having means to spray water about the jet of sand to settle the dust.

Still another object of this invention is to provide a device of the character described so constructed that the water jacket may be removed if it is desired to sand blast without spraying water.

Another object of this invention is to provide a device of the character described which shall be easy to assemble and manipulate, which shall be relatively inexpensive to manufacture and yet practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawing, in which are shown various possible illustrative embodiments of this invention.

Fig. 1 is an axial cross-sectional view through a sand blasting nozzle embodying the invention attached to a sand blast hose and a water hose;

Fig. 2 is a front end view of the structure shown in Fig. 1;

Fig. 3 is a cross-sectional view taken on line 3—3 of Fig. 1; and

Fig. 4 is a side elevational view of the structure shown in Fig. 1.

Referring now in detail to the drawing, 10 designates a sand blasting nozzle embodying the invention. The same comprises a sand hose 11 fitted onto the neck 12 of an adaptor or pipe 13. Said neck 12 may be formed with serrations 12a to hold the hose.

The adaptor 13 is tubular as shown in Fig. 1, and is provided with external, steep pitched screw threads 16 at its forward end. Screwed onto the threads 16 is a union 17 having internal threads 18 to receive the threads 16. The union 17 has an end wall 19 formed with a central opening 20. Extending through the opening 20 is a sand nozzle 22.

Said nozzle 22 is formed with a flange 23 at its rear end disposed within the union and contacting the inner surface of end wall 19 of the latter. The nozzle 22 is somewhat tapered toward its outer end. It is formed with a central through opening 24 enlarged at its rear end as designated

by numeral 25. Sand is supplied by hose 11 and is blown by compressed air through the nozzle 22.

Means is provided to settle the dust around the jet of sand. To this end there is screwed to union 17 a water jacket 30. The union 17 is formed with external screw threads 31 to receive complementary threads of jacket 30, as will be explained hereinafter.

The jacket 30 comprises an outer cylindrical wall 32 and an inner substantially concentric wall 33, interconnected by a front end wall 34. The inner wall 33 has a tapering inner through opening 35 to receive the nozzle 22. Extending from wall 32 is an enlarged cylindrical wall 38 forming an inner shoulder 39 at the bottom of said enlarged wall. The enlarged wall 38 is formed with internal threads 40 to receive the threads 31 of the union.

At the rear end of the inner wall 33 is a shoulder 33a in the same plane as the shoulder 39. A gasket 41 contacts the shoulders 39, 33a.

It will be noted that the end wall 19 of union 17 contacts said gasket to close the rear end of the water jacket and seal the same. The space or chamber 45 between the inner wall 33 and the outer wall 32 forms a chamber for receiving water in the manner described hereinbelow.

Wall 38 may be formed with ribs 46 to afford a good grip for tightening the jacket on the union. 30 The union 17, if desired, may furthermore be formed with spaced openings 47 to receive a spanner wrench.

The end wall 34 is formed with a plurality of equiangularly spaced, forwardly and outwardly divergent small openings 50 through which the water passes from the chamber 45. Wall 32 is formed with an integral, rearwardly and outwardly inclined pipe 52. Screwed to pipe 52 is a water valve or cock 53 to control supply of water to the jacket. Attached to said valve is a nipple 53a and attached thereto by means of a union 54 is a water hose 55.

It will now be understood that water is supplied to the chamber 45 and causes a spray through the openings 50 surrounding the jet of sand which issues from the nozzle 22 to settle the dust about said jet.

It will thus be seen that there is provided a device in which the several objects of this invention are achieved, and which is well adapted to meet the conditions of practical use.

As various possible embodiments might be made of the above invention, and as various changes might be made in the embodiments above set forth, it is to be understood that all matter here-

in set forth or shown in the accompanying drawing is to be interpreted as illustrative and not in a limiting sense.

Having thus described my invention, I claim as new and desire to secure by Letters Patent:

1. A sand blasting nozzle comprising an adaptor to which a sand hose may be connected, a union screwed to said adaptor, a sand nozzle, said union being adapted to connect said sand nozzle to said adaptor, a water jacket surrounding said nozzle, said water jacket having spray openings surrounding said nozzle, and means to attach said jacket to said union.
2. In combination, a sand nozzle, means to supply sand to said nozzle, a water jacket surrounding said nozzle, said water jacket being provided with a plurality of spray openings at one end surrounding said nozzle, said spray openings being equiangularly spaced and forwardly divergent, said jacket being open at its opposite end, means to attach said jacket to said nozzle, and means to close said open end of said jacket upon attaching said jacket to said nozzle.
3. In combination, a sand nozzle, means to supply sand to said nozzle, a water jacket surrounding said nozzle, said water jacket being provided with a plurality of spray openings surrounding said nozzle, said spray openings being equiangularly spaced and forwardly divergent, and means to supply water to the water jacket, means to attach said jacket to said nozzle, said jacket extending forwardly beyond the forward end of said nozzle, and having an outwardly flaring inner surface disposed forwardly of the forward end of said nozzle.
4. In combination, a tubular adaptor having means to receive a hose and provided with external screw threads, a union screwed to said screw threads, a sand nozzle connected to said adaptor by said union, a water jacket surrounding said nozzle and having inner and outer annular walls, and a front end wall interconnecting said inner and outer walls and forming a water chamber, said front end wall being formed with a plurality of spaced openings, and means to detachably connect said jacket to said union.
5. In combination, a tubular adaptor having means to receive a hose and provided with external screw threads, a union screwed to said screw threads, a sand nozzle connected to said adaptor by said union, a water jacket surrounding said nozzle and having inner and outer annular walls, and a front end wall interconnecting said inner and outer walls and forming a water chamber, said front end wall being formed with a plurality of spaced openings, said openings being divergent forwardly, and means to detachably attach said jacket to said union.
6. In combination, a tubular adaptor having means to receive a hose and provided with external screw threads, a union screwed to said screw threads, a sand nozzle connected to said adaptor by said union, a water jacket surrounding said nozzle and having inner and outer annular walls, and a front end wall interconnecting said inner and outer walls and forming a water chamber, said front end wall being formed with a plurality of spaced openings, said openings being divergent forwardly, said outer wall being provided with an integral rearwardly and outwardly inclined pipe extension, and means to supply water to said water jacket through said pipe extension, and means to detachably attach said jacket to said union.
7. In combination, a tubular adaptor having means to receive a hose and provided with external screw threads, a union screwed to said screw threads, a sand nozzle connected to said adaptor by said union, a water jacket surrounding said nozzle and having inner and outer annular walls, a front end wall interconnecting said inner and outer walls and forming a water chamber, said front end wall being formed with a plurality of spaced openings, said openings being divergent forwardly, said outer wall being provided with an integral pipe extension, means to supply water to said water jacket through said pipe extension, and a valve to control supply of water to said water jacket, and means to detachably attach said jacket to said union.
8. In combination, a tubular adaptor having means to receive a hose and provided with external screw threads, a union screwed to said screw threads, a sand nozzle connected to said adaptor by said union, a water jacket surrounding said nozzle and having inner and outer annular walls, a front end wall interconnecting said inner and outer walls and forming a water chamber, said front end wall being formed with a plurality of spaced openings, said openings being divergent forwardly, said outer wall being provided with an integral pipe extension, means to supply water to said water jacket through said pipe extension, a valve to control supply of water to said water jacket, and said outer wall being screwed to said union.
9. In combination, a tubular adaptor having means to receive a hose and provided with external screw threads, a union screwed to said screw threads, a sand nozzle connected to said adaptor by said union, a water jacket surrounding said nozzle and having inner and outer annular walls, a front end wall interconnecting said inner and outer walls and forming a water chamber, said front end wall being formed with a plurality of spaced openings, said openings being divergent forwardly, said outer wall being provided with an integral pipe extension, means to supply water to said water jacket through said pipe extension, a valve to control supply of water to said water jacket, said outer wall being screwed to said union, and means on said union for sealing the rear of said chamber.
10. In combination, an adaptor formed with a screw threaded portion, a sand nozzle contacting the forward end of the adaptor, a union having internal screw threads screwed to said screw threaded portion, said union having an end wall formed with a central opening through which said nozzle passes, said nozzle being formed with a flange pressed against said adaptor by said end wall, a water jacket surrounding said nozzle and having an inner wall, and an outer wall connected by a wall at the forward end of said jacket, the outer wall of said jacket having an internally screw threaded portion screwed to external screw threads on said union.
11. In combination, an adaptor formed with a screw threaded portion, a sand nozzle contacting the forward end of the adaptor, a union having internal screw threads screwed to said screw threaded portion, said union having an end wall formed with a central opening through which said nozzle passes, said nozzle being formed with a flange pressed against said adaptor by said end wall, a water jacket surrounding said nozzle and having an inner wall, an outer wall connected by a wall at the forward end of said jacket, the outer wall of said jacket having an internally screw threaded portion screwed to external screw threads.

threads on said union, said inner and outer walls of said jacket having shoulders, a gasket on said shoulders, and the end wall of said union being adapted to press said gasket against said shoulders.

12. In combination, an adaptor formed with a screw threaded portion, a sand nozzle contacting the forward end of the adaptor, a union having internal screw threads screwed to said screw threaded portion, said union having an end wall formed with a central opening through which said nozzle passes, said nozzle being formed with a flange pressed against said adaptor by said end wall, a water jacket surrounding said nozzle and having an inner wall, an outer wall connected by a wall at the forward end of said jacket, the outer wall of said jacket having an internally screw threaded portion screwed to external screw threads on said union, said inner and outer walls of said jacket having shoulders, a gasket on said shoulders, and the end wall of said union being adapted to press said gasket against said shoulders, said outer wall having a rearwardly inclined integral pipe extension to receive water for said jacket.

13. In combination, an adaptor formed with a screw threaded portion, a sand nozzle contacting the forward end of the adaptor, a union having internal screw threads screwed to said screw threaded portion, said union having an end wall formed with a central opening through which said nozzle passes, said nozzle being formed with a flange pressed against said adaptor by said end wall, a water jacket surrounding said nozzle and having an inner wall, an outer wall connected by a wall at the forward end of said jacket, the

outer wall of said jacket having an internally screw threaded portion screwed to external screw threads on said union, said inner and outer walls of said jacket having shoulders, a gasket on said shoulders, the end wall of said union being adapted to press said gasket against said shoulders, said outer wall having a rearwardly inclined integral pipe extension to receive water for said jacket, and a valve on said pipe extension.

14. A sand blasting nozzle comprising an adaptor to which a sand hose may be connected, a union screwed to said adaptor, a sand nozzle, said union being adapted to connect said sand nozzle to said adaptor, a water jacket surrounding said nozzle, said water jacket having spray openings surrounding said nozzle, and means to attach said jacket to said union, said jacket being open at one end, and means on said union to close said end of said jacket.

15. In combination, a tubular adaptor having means to receive a hose and provided with external screw threads, a union screwed to said screw threads, a sand nozzle connected to said adaptor by said union, a water jacket surrounding said nozzle and having inner and outer annular walls, a front end wall interconnecting said inner and outer walls and forming a water chamber, said front end wall being formed with a plurality of spaced openings, said outer wall being provided with an integral pipe extension, means to supply water to said water jacket through said pipe extension, and means to attach said water jacket to said union.

THOMAS SORRENTINO.
